UNITED STATES PATENT OFFICE.

CLELAND DAVIS, OF ENGLEWOOD CLIFFS, NEW JERSEY, ASSIGNOR TO NATIONAL TORPEDO COMPANY, OF AUGUSTA, MAINE, A CORPORATION OF MAINE.

MEANS FOR DECREASING THE VISIBILITY OF THE WAKE OF AUTOMOBILE TORPEDOES.

Application filed November 28, 1923. Serial No. 677,463.

To all whom it may concern:

Be it known that I, CLELAND DAVIS, a citizen of the United States, residing at Englewood Cliffs, county of Bergen, and State 5 of New Jersey, have invented certain new and useful Improvements in Means for Decreasing the Visibility of the Wake of Automobile Torpedoes; and I do hereby declare the following to be a full, clear, and 10 exact description, such as will enable others skilled in the art to which it appertains to make and use the same:

My present invention relates to improved means for decreasing the visibility of the 15 wake of automobile torpedoes, which are driven by compressed air or other gas.

With the present type of automobile torpedoes, the propelling power comprises a tank of air under very high pressure, which 20 escapes through a reducing valve, and the expanded air is heated before going to the turbines which drive the propellers in reverse directions. The escape air after doing its work is generally allowed to flow 25 through the inner hollow propeller shaft and escapes into the sea in the form of large bubbles or globules. These bubbles expand as they rise in the water and finally burst at the top of the water causing a very visible 30 wake.

This wake is so apparent under normal weather conditions that the approach of the torpedo may be detected, and the vessel or 35 vessels at whom it is aimed may readily avoid the same by maneuvering.

Such was found to be the case in the battle of Jutland and has been often noted in practice before and since then.

I have found that by breaking up the air 40 into very small globules before it is allowed to escape into the water, the size and explosive effect of the bubbles and the corresponding visibility of the wake of the torpedo may largely be decreased, if not actually eliminated for most practical purposes.

In order to accomplish this result I provide a suitable foraminous expansion chamber in the rear of the present escape outlet for the gases from which the escaping air 50 flows in comparatively minute globules, and these globules are directed in various directions through the water and rise to the surface in such a way as not to have the explosive effect of the larger globules or bubbles already referred to.

I have shown the invention in two forms and adapted for use either with a torpedo having propeller guards projecting in the rear of the propellers or with the torpedo in which such guards are omitted and in which there are no fixed portions of the 60 torpedo in the rear of the hollow propeller shaft.

My invention will be more fully understood after reference to the accompanying 65 drawings, in which:

Figure 1 shows the torpedo provided with propeller guards with a foraminous hose attached through the rear thereof, said hose being closed at its rear end; 70

Figure 2 is a sectional view on a larger scale, showing the mode of attaching the hose to the torpedo; and

Figure 3 is a sectional elevation showing the cap or casing connected to the rear end 75 of the hub of the rear propeller in an automobile torpedo which is devoid of propeller guards, said cap or casing rotating with said hub, and forming a foraminous chamber into which the escaping air passes. 80

Referring first to Figs. 1 and 2, A represents the main body of the torpedo, which is constructed of the usual or preferred type, and which is provided with the usual propeller guards B between which the propellers C and D are journaled in the usual way. These propeller shafts are in the form of concentric tubes C' and D', and the exhaust air from the engine (not shown) passes through the inner tube or rear propeller shaft and ordinarily flows into the sea, but according to my invention, I attach a flexible hose E, which may be made of rubber or other suitable material, preferably reinforced with wire coils F and closed at 95 the rear end with a cap G, preferably of ogival or pointed construction, so as to reduce the resistance, as it is drawn through the water.

This hose is provided with a number of 100 small openings e of any suitable size, so that the total area of the openings would be preferably greater than the cross-section through the inner propeller shaft.

These openings are preferably inclined 105 rearwards and outwards as shown in Fig. 2, so as to create suction as the torpedo moves rapidly through the water, thus to lessen the back pressure of the exhaust.

In order to diminish friction the hose 110

may be coated with graphite or albumen, or other material which will tend to lessen the skin friction as it is drawn through the water.

5 By this arrangement, the escaping air will be broken up into very fine globules before it enters the water, and it will be directed in various directions into the water and will not rise in large globules or 10 bubbles.

The hose applied to the rear of the torpedo, as stated, will also serve to steady the torpedo in its flight through the water after the manner of a tail to a kite.

15 In the form of device shown in Fig. 3, the propeller guards are omitted and there is nothing in the rear portion of the torpedo to which the hose or the like can be attached, and in such cases I provide a 20 suitable cap attached to the hub of the rear propeller, such as is shown at E'. This cap is preferably tapered to follow the contour of the torpedo so as to provide the desired stream lines or "fair weather" whereby the 25 resistance due to skin friction is largely avoided. This hollow cap E' is provided with a plurality of holes e', which preferably are inclined rearward and outward, so that the suction incident to the forward 30 movements of the torpedo in the water will tend to decrease the exhaust pressure. These holes may be made of any desired fineness, and the total area of the holes should preferably be greater than the cross-sectional 35 area of the passage through the inner propeller shaft, so that the addition of the ex-

pansion chamber will not materially increase the back pressure.

In either form of the device as hereinbefore described, the air from the engine escapes through the inner propeller tube and into the expansion chamber, from which it escapes through a number of small perforations, the escaping air being directed in various directions through the water and rising to the surface in due course, where small bubbles only will be formed and the bursting of these small bubbles will not be noticeable under the normal weather conditions that prevail at sea.

40 While I have shown two forms of the invention adapted for use with an automobile torpedo, it will be obvious that the same general principle may be applied to other forms of the device, and I do not 45 mean to limit the invention to any particular form or arrangement, except as particularly pointed out in the claim.

Having thus described my invention, 50 what I claim and desire to secure by Letters Patent of the United States is:

An attachment for automobile torpedoes 55 propelled by compressed air or other gas, comprising an expansion chamber carried at the rear of the torpedo having a plurality of perforations in its outer walls, the said 60 perforations being inclined outward and rearward to facilitate the exhaust, whereby the escaping air or gas is divided into a 65 number of fine streams issuing in divergent 70 directions.

CLELAND DAVIS.
